UNITED STATES PATENT OFFICE

159,790

COLLAPSIBLE BASKET

Ann Ellis, Victoria, Hong Kong

Application May 4, 1949, Serial No. 2,435

Term of patent 14 years

(Cl. D58—4)

To all whom it may concern:

Be it known that I, Ann Ellis, a citizen of the United States, residing at 7 Bowen Road, Victoria, in the Colony of Hong Kong, whose post office address is 7 Bowen Road, Victoria, in the Colony of Hong Kong, have invented a new, original, and ornamental Design for a Collapsible Basket, of which the following is a specification, reference being had to the accompanying drawing, forming part hereof.

In the drawing,

Fig. 1 is a top plan view of a collapsible basket showing my new design;

Fig. 2 is a side elevational view thereof, showing the basket in collapsed position; Fig. 3 is an end elevational view of Fig. 2; Fig. 4 is a front elevational view of Fig. 1, and Fig. 5 is a perspective view showing the basket in expanded and closed position.

I claim:

The ornamental design for a collapsible basket, as shown.

ANN ELLIS.
